UNITED STATES PATENT OFFICE.

WILLIAM H. THOMAS, OF COVINGTON, TENNESSEE.

BRACE FOR PLOWS.

SPECIFICATION forming part of Letters Patent No. 772,757, dated October 18, 1904.

Application filed May 21, 1904. Serial No. 209,083. (No model.)

To all whom it may concern:

Be it known that I, WILLIAM H. THOMAS, a citizen of the United States, residing at Covington, in the county of Tipton and State of Tennessee, have invented certain new and useful Improvements in Braces for Plows; and I do hereby declare the following to be a full, clear, and exact description of the invention, such as will enable others skilled in the art to which it appertains to make and use the same.

My invention relates to plows.

It has for its object to improve the method of bracing the beam and post.

To this end the invention consists of brackets, preferably made of suitable light metal of requisite strength, applied one on each side to connect the beam and post, the handles fitting over said brackets.

In the accompanying drawings, illustrating the preferred embodiment of my invention, Figure 1 is a side elevation of a plow beam and post connected by my improved brace and the handle secured to said post over the portion of said brace extending along the post. Fig. 2 is a similar view with a portion of the handle broken away, disclosing the full outline of the brace; and Fig. 3 is a sectional view through the post-braces and handles, taken on the line $\alpha-\alpha$ of Fig. 1.

Referring more particularly to the drawings, the braces 1 are preferably made of malleable iron and come "rights" and "lefts" to fit both sides of the beam 2 and post 3. Each brace is composed of a straight rod-like portion, preferably flattened on one side and rounded on the other, adapted to extend along the post, a portion 5 to extend along the beam connected to the part 4 by branches 6, 7, one joining said part 2 near its extremity 40 and the other near its center, and a round rod or bar 8, extending between the extremities of said other portions. The portion 5 is also preferably flattened on the back and round at the front. The brace or bracket is preferably made integral and is generally triangular in shape.

The brackets are applied, as shown in the drawings, along the faces of the beam and post and secured by bolts passing through said beam and post and suitable apertures in 50 said brackets. The handles 9 are applied over the portion 4 of the bracket and are grooved at their ends for that purpose, as shown in Fig. 3.

The invention is cheap, simple, durable, 55 and strong. The brackets can be quickly applied to the parts as the plow is being constructed and when applied will hold the parts securely in place. I am aware that changes may be made in my invention without departing from the spirit or sacrificing the advantages thereof. For instance, the shape of the rods or sides of the bracket may be changed by making them angular in cross-section and the angles between said sides varied at will. 60 I therefore reserve the right to make such changes as fairly fall within the scope of my invention.

Having thus described my invention, what I claim as new, and desire to secure by Letters 70 Patent, is—

1. In a plow, the combination with the beam, post and handles, of a brace comprising a portion extending along the post under the handles, a portion extending along the beam 75 and a portion joining the extremities of the other portions and extending between the beam and post.

2. A plow-frame comprising a beam, a post, a brace comprising a portion extending along 80 said post, a portion extending along said beam, and a portion joining the extremities of said other portions and extending between said beam and post, and handles having a groove adapted to fit over said portion of said 85 bracket extending along said post.

In testimony whereof I affix my signature in presence of two witnesses.

WILLIAM H. THOMAS.
